(57) **CLAIM**

The ornamental design for a ceiling rail connector, as shown and described.

DESCRIPTION

FIG. 1 is a front elevation view of a ceiling rail connector, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a front perspective view thereof.

The broken lines depict portions of the article that form no part of the claim.
